UNITED STATES PATENT OFFICE.

JOHN HAWLEY TAUSSIG, OF PHILADELPHIA, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

BASE-CLOSURE FOR VERTICAL GAS-RETORTS.

1,105,583.

Specification of Letters Patent.

Patented July 28, 1914.

Application filed January 20, 1913. Serial No. 743,027.

To all whom it may concern:

Be it known that I, JOHN HAWLEY TAUS-
SIG, a citizen of the United States, residing
at the city of Philadelphia, in the county
of Philadelphia and State of Pennsylvania,
have invented a certain new and useful Base-
Closure for Vertical Gas-Retorts, of which
the following is a specification.

In the operation of vertical gas retorts
leakage not infrequently occurs past the
doors which constitute the bottom closures
of the retorts. This leakage results in the
escape of gas which is of course wasteful.
Moreover, the gas frequently becomes
ignited and burns producing undue heating
of the parts and positive injury to, if
not destruction of, the apparatus or parts
thereof.

My invention is based upon the existence
of sufficient gas pressure inside the retorts
and above the bottom doors for causing leakage
at the doors although there may be
practically no pressure at the tops of the
retorts where the gas is usually led off by
an exhaust through a water seal. In ac-
cordance with my invention gas is led off
not only from the tops but also from the
bottoms of the retorts so that there is not
sufficient gas pressure above the doors for
causing leakage.

The principal objects of my invention are
to prevent leakage at the doors; to provide
convenient and reliable apparatus for draw-
ing off gas above the sealing portions of the
doors; and to provide for cleaning the ducts
by which the gas is drawn and led off.

The invention comprises the improve-
ments to be claimed at the end hereof and to
be first described in connection with the ac-
companying drawings illustrating certain
embodiments of the invention chosen from
other embodiments for the sake of explana-
tion.

In the drawings Figure 1, is an elevational
view, partly in section, illustrating one em-
bodiment of the invention. Fig. 2 is a simi-
lar view drawn to an enlarged scale and
illustrating details of construction. Fig. 3,
is a sectional view drawn to an enlarged
scale and taken at right angles to the sec-
tion of Fig. 2. Fig. 4, is a bottom plan

view, and Fig. 5, is a sectional view illus-
trating a modification.

A base closure for vertical gas retorts em-
bodying features of the invention comprises 55
a door having two parts with accessible gas
space between them and whereof one part
operates as a seal and the other part as a
charge support, in coöperation with a door
frame provided with a gas off-take commu- 60
nicating with the accessible gas space.

In the drawings, Figs. 1-4, 1, is the ac-
cessible gas space, and in Fig. 5, 1^a, is the
accessible gas space. In Figs. 1-4, the part
2, is the charge supporting cover, and the 65
part 3, operates as a seal. In Fig. 5, the
part 2^a, operates as a charge supporting
cover, and the part 3^a, operates as a seal.
In Figs. 1-4, the door frame 4, is provided
with gas off-takes 5, communicating with the 70
space 1. In Fig. 5, the door frame 4^a, is
provided with gas off-takes 5^a, communi-
cating with the space 1^a. As shown the gas
off-takes 5 and 5^a, are alined so that they
can be cleaned as by means of a tool inserted 75
at 6.

7, is an eduction pipe communicating with
the gas off-takes and with a hydraulic seal 8,
from which gas is drawn as by means of an
exhaust 9, which discharges into suitable 80
gas storage apparatus.

As shown in Figs. 1-4, the parts 2 and
3, are united as at 10, toward one side of the
door and at the opposite side these parts are
supported by a support 11. The area of the 85
part 3, exceeds the area of the part 2, so that
gas can enter the space 1, from the interior
of the lower part of the vertical retort 12.
This is the sense in which the space 1, is
said to be accessible, meaning that gas can 90
enter while the retort charge is supported
above it. In these figures the bottom closure
is supported by a cotter bar 13, pivoted at 14,
and detachably clamped at 15.

In Fig. 5, the parts 2^a and 3^a, are pivoted 95
at 16 and 17, and detachably clamped at 18
and 19. The part 2^a, sustains the charge but
permits gas to reach the accessible space 1^a.
The door 3^a, seals the gas, and the gas is
drawn off at 5^a. 20, are gas eduction connec- 100
tions at the tops of the retorts, and 21, are
portions of the same.

It will be obvious to those skilled in the art to which the invention relates that modifications may be made in details hence I do not limit myself in that regard or more than the prior state of the art may require, but

Having thus described my invention what I claim is:

1. A base closure for vertical gas retorts comprising the combination of a door having two parts with accessible gas space between and whereof one part operates as a seal and the other as a charge support, and a door frame provided with a gas off-take communicating with said space, substantially as described.

2. A base closure for vertical gas retorts comprising the combination of a door, a charge supporting cover applied near one edge of the face of the door with accessible space between the cover and door, a support between the cover and door near the other edge of the latter, and means for drawing off gas from said space.

3. A base closure for vertical gas retorts comprising the combination of a door frame having door openings, aligned gas ducts open-

ing through the walls of the openings, doors adapted to seal the openings below the ducts, and charge supporting covers arranged above the ducts and adapted to permit of the passage of gas thereto.

4. A base closure for vertical gas retorts comprising the combination of a door frame having door openings, gas ducts opening through the walls of the openings, doors 35 adapted to seal the openings below the ducts, and charge supporting covers arranged above the ducts and adapted to permit of the passage of gas thereto.

5. A base closure for vertical gas retorts 40 comprising the combination of a door frame provided with openings and with ducts communicating with the openings, means for drawing off gas through the ducts, doors below the ducts, and charge supporting covers 45 above the ducts past which gas may be drawn to the ducts.

JOHN HAWLEY TAUSSIG.
